AUTOMATIC CONTACT PRINTER

Karl J. Kallenborg, Minneapolis, Minn., assignor to Prestige Photo Products, Inc., Minneapolis, Minn., a corporation of Minnesota

Filed Mar. 6, 1967, Ser. No. 6,086

Term of patent 14 years

(Cl. D61—1)

FIG. 3

FIG. 4

FIGURE 1 is a front perspective view of an automatic contact printer embodying my new design;

FIGURE 2 is an end elevational view thereof;

FIGURE 3 is a top plan view thereof;

FIGURE 4 is a fragmentary front elevational view thereof;

FIGURE 5 is a rear elevational view thereof; and

FIGURE 6 is an end elevational view thereof as viewed from the direction opposite that of FIGURE 2.

I claim:

The ornamental design for an automatic contact printer, as shown.
